UNITED STATES PATENT OFFICE.

VIRGIL TILDEN WRIGHT, OF CORSICANA, TEXAS.

AUTOMOBILE-ELEVATOR.

1,248,235.

Specification of Letters Patent.

Patented Nov. 27, 1917.

Application filed April 2, 1917. Serial No. 159,182.

To all whom it may concern:

Be it known that I, VIRGIL TILDEN WRIGHT, a citizen of the United States, and a resident of Corsicana, in the county of Navarro 5 and State of Texas, have invented an Improvement in Automobile-Elevators, of which the following is a specification.

My invention is an improvement in automobile elevators, and has for its object to 10 provide mechanism of the character specified, which may be arranged in garages and like places for elevating the car and supporting it with the tires out of contact with the floor, wherein the movement of the car 15 is utilized to operate the elevator.

In the drawings:

Figure 1 is a top plan view of the improved elevator with parts in section.

Fig. 2 is a side view.

Fig. 3 is a section on the line 3—3 of Fig. 20 1, looking in the direction of the arrows adjacent to the line.

Figs. 4 and 5 are sections on the lines 4—4 25 and 5—5 of Fig. 2, each view looking in the direction of the arrows adjacent to the line.

The present embodiment of the invention 30 comprises a base or trackway of substantially rectangular form and consisting of spaced side bars 1 connected by cross bars 2 and 3, and by a cross plate 4. The cross plate 4 is arranged in vertical position above the side bars, and a carriage is mounted to run upon the base or trackway.

This carriage comprises spaced side bars 35 5, which register with the side bars 1 of the base, and the side bars are connected by cross bars 6 at their ends. The carriage is further braced by inclined brace rods 7, and near each end the carriage has pairs of 40 buffer blocks 8 and 9, for engagement by the front and rear axles of the automobile 10. Rollers 11 are journaled transversely of the carriage near the ends thereof, the said rollers having journal pins 12 which are journaled 45 in bearing plates 13 on the side bars 5 of the carriage. These rollers are adapted to run upon the upper faces of the bars 1, and it will be noticed that said bars have inclines 14 and 15 upon which the rollers 50 run. These inclines are similar, the inclines 14 being at that end of the base remote from the cross plate 4, while the inclines 15 are near the other end.

The elevator is of a width such that the 55 car may straddle the same, and it will be

evident that when the car is run over the elevator, and the axles engage the buffers 8 and 9, the carriage will be moved forward, and as the rollers travel up the inclines, the carriage and the car will be elevated. 60

Latch mechanism is provided for holding the carriage in the position shown in Fig. 3. The said mechanism comprises a resilient ratchet bar 16, which is secured at one end to the cross plate 4. The teeth of the bar 65 face toward the plate 4, and they are adapted to engage the front axle to lock the carriage in elevated position. It will be noticed from an inspection of Fig. 3 that the ratchet bar inclines downwardly from the plate 4, 70 and the inner end thereof is connected to the crank arm 17 of a crank shaft 18 journaled transversely of the base in the bars 1.

The connection is made by an eye-bolt 19, and it will be noticed that the ratchet 75 plate is movable longitudinally of the bolt between stops 20 and 21 on the eye bolt. The handle 22 of the crank shaft has connected therewith an operating member in the form of a cord 23, and a coil spring 24, 80 and the spring acts normally to hold the parts in the position of Figs. 1, 2 and 3, that is with the crank upward. The cord passes forwardly from the handle 22 over direction elements 25 which are mounted on 85 a standard 26 having a lateral arm 27 extending toward the shaft 18. This standard extends outwardly from the base and then upwardly and toward the crank arm, to bring the free end of the cord in position 90 to be grasped by the driver seated in the car. This free end of the cord is provided with a handle or grip 28, and it will be evident that when downward traction is made upon the grip the shaft 18 will be 95 oscillated in a direction to pull down the inner end of the ratchet bar, to release the front axle of the carriage. The ratchet bar is normally pressed upward by a coil spring 30, which encircles a bolt 31 arranged between the cross bar 3 and the ratchet bar and passing through the said cross bar and ratchet bar. A stop 32 is arranged above the bar, and the spring acts normally to press the bar upwardly and to hold it in 100 position for engagement by the front axle. 105

A buffer is provided for checking the momentum of the carriage, the said buffer comprising a bar 33 which is arranged transversely of the base adjacent to the cross 110

plate 4. Bolts 34 are passed through the buffer bar and the cross plate, and coil springs 35 encircle the bolts between the plate and the bar. These springs normally 5 press the bar toward the carriage, and the bolts are passed through nuts 36 secured to the cross plate 4, in order that the tension of the springs may be adjusted.

In operation, with the parts in the position of Fig. 2, the car is driven over the carriage. As soon as the axles engage the buffer blocks 8 and 9 the carriage will commence to travel up the inclines 14 and 15, and the front axle will pass over the teeth 10 of the ratchet bar. As soon as the carriage 15 engages the buffer bar its momentum will be checked and at this time the wheels of the car will be out of contact with the floor of the garage, as indicated in Fig. 3. The 20 ratchet bar holds the carriage from downward movement.

When it is desired to run the car out, the driver starts the engine, releases the ratchet 25 bar, and the weight of the car and the carriage will cause the carriage to run down the inclines. As soon as the wheels come

in contact with the floor the car will begin to move under its own power.

I claim:

A device of the character specified, comprising a base frame and a carriage, the frame having pairs of inclines and rollers on the carriage and running upon the inclines for raising and lowering the carriage, said carriage having stops for engagement by the axles of a motor vehicle to move the carriage up the inclines, normally operative means for engaging the axle of the vehicle to prevent retrograde movement of the carriage and vehicle and releasable at 30 will, and a buffer on the base frame for engagement by the carriage when the wheels of the vehicle are out of contact with the ground, said engaging means for the axle comprising a resilient ratchet bar, and means operable intermediate the ends of the 35 base frame for releasing the ratchet bar. 40 45
